UNITED STATES PATENT OFFICE

2,482,253

WASHING MACHINE AGITATOR

Nicholas L. Etten, Waterloo, Iowa

Application August 30, 1945, Serial No. 613,666

16 Claims. (Cl. 68—53)

1

This invention relates to a domestic washing machine of the regular tub type incorporating cooperative mechanisms for first carrying out the washing operation and secondly to spin the tub and its contents to spin dry the washed clothes.

It is one of the main objects of the washing machine of the present invention to provide an agitator within the confines of the washing tub that operates to produce a bellows action within the tub water to direct water currents in predetermined directions to aid the agitator in the washing of the clothes.

Another object of the above described structure is to provide a bellows unit that definitely produces a water agitating action in conjunction with the directed water currents of the above noted type.

Another object of the present invention is to provide the mechanical unit that is herein embodied within the confines of the tub to perform the actions described and which includes further mechanism to cause bodily rotation of the entire unit upon the axial center line of the washing machine tub.

A further object of the washing machine of the present invention is to provide an agitating and water current developing unit of the type described which is entirely driven and actuated from mechanism housed and disposed complete within the confines of such a bellows unit. In this manner, the entire mechanism is housed within the tub proper and is pivotally carried on suitable bearings permitting the entry of a drive shaft into the interior of the bellows unit for actuating the mechanism confined within the operable head comprising the bellows agitating and water current producing unit.

Amongst other objects, it is another feature of this invention to produce a drive arranged for independently actuating the bellows unit head and its associated mechanisms and to also incorporate a dual drive for the purpose of permitting the drive from the same source to provide the power for spinning the entire tub to spin dry the clothes that have been washed therein.

Certain other objects of the present invention are to produce several modified arrangements to obtain a water propelling action for the purpose of slowly rotating the agitating unit within the tub and upon the axial center line thereof.

2

All other objects and advantages inherent in the constructions herein disclosed and described shall hereinafter appear in the following detailed explanation thereof having reference to the several figures disclosed in the accompanying drawings forming a part of this specification.

In the drawings:

Fig. 1 is a general vertical cross sectional view through a preferred embodiment of washing machine incorporating the principles relating to the present invention;

Fig. 2 is an enlarged vertical axial cross sectional view of the bellows agitator and the associated bearing structures adjacent thereto;

Fig. 3 is a plan view of the bellows type agitator shown in Fig. 2;

Fig. 4 is an end view of the bellows agitator as it appears when viewed from the left in Fig. 3, the opposite end being a duplicate as the agitator is built symmetrically;

Fig. 5 is a perspective view of the main housing unit of the bellows agitator;

Fig. 6 is a general side view of a modified construction of agitator utilizing a different means to cause axial rotation of the entire unit upon its pivotally supported mountings in the tub bottom;

Fig. 7 is a horizontal cross sectional view of the agitator of Fig. 6 as seen along the line 7—7 in Fig. 6; and

Fig. 8 is a horizontal cross sectional view of another modification of bellows type agitator illustrating a still different arrangement of housing therefor for the purpose of producing bodily rotation thereof during the agitating action.

It should be apparent at this time from the objects hereinbefore presented and the description of the figures that the present washing machine incorporates a novel agitator having dual means for producing directional dispersion of water currents that definitely effect the movement of the clothes within the tub, such current acting in combination with a definite water agitating action produced by the bellows or movable flaps of the agitator; most of the aforesaid combined washing features being incorporated in a bellows head unit that revolves bodily producing a 360° sphere of action within the cylindrical column of water within the tub of the present washing machine. Furthermore, all of these actions

can be terminated at the end of the washing period prescribed and thereafter the tub drained. Manual control means are employed thereafter so that the tub can be driven from the same source of power that operated the agitating unit which power source can now be directed to revolve the washing tub to spin dry the clothes therein.

Referring to Fig. 1, the machine comprises, in general, a supporting base 1 adapted for housing the washing machine power drive mechanisms 2 that are driven from the motor 3 supported from the base. A drain tub 4 is mounted upon the upper peripheral edge of the base 1 and is stationary with respect thereto, while a movable tub 5 nests within the stationary drain tub and is suitable mounted for pivotal spinning rotation upon the vertical axial center of the washing machine. A lid 6 provided with a peripheral gasket 7 is adapted to rest upon a circumferential rim 8 formed at the upper edge of the drain tub 4. All of the foregoing described closure means are for preventing water from spilling out of the washing machine and are formed and arranged particularly for that purpose. The position of the lid gasket and the peripheral seal 8 formed at the upper end of the drain tub 4 are located to prevent centrifugally discharged water and suds from leaving the entire tub enclosure during the dry spinning operation of the tub 5. The upper edge of the tub 5 is suitably beaded or otherwise formed as at 9 and spaced below the parting line between the lid 6 and the tub 5 so that all of the centrifugally discharged water will be directed against the vertical side portion of the tub 5 and suitably drained therefrom to the bottom of the tub.

The bottom of the tub 4 is provided with a relatively large discharge duct or conduit 10 having a suitable valve 11 controlled by the valve handle 12 located externally of the base 1. Conduit 10 is sufficiently large primarily for the purpose of permitting quick draining of the expelled water from within the spinner tub 5 and also to permit the passage of small articles of clothing which should by accident find their way over the top of the bead 9 of the spinning tub. Larger articles would not be discharged through the clearances provided.

The bellows agitating unit is positioned centrally with respect to the spinner tub 5 and is generally indicated by the reference numeral 13. This agitator unit is best understood by referring to Figs. 1 and 2 and comprises a main housing 14 having a box base 15 with parallel upstanding sides 16 and 17. A bearing 18 supports the housing 14 through connection with the bottom of the box base 15, this bearing 18 being journalled for rotation upon a vertical axis within the upper end of the driving sleeve 20 suitably secured in water tight contact with the spinner tub 5. Bearing 18 also includes suitable sealing means and has rings 21 to prevent leakage of water from within the tub 5 through the bearing structure 18 and into the interior of the driving sleeve 20.

A pair of oppositely related flaps 22 and 23 providing closure members for the housing 14 are pivotally supported upon a cross pin 24 extending between the upper portions of the side walls 16 and 17 of the housing 14. These swingable flaps 22 and 23 are provided with side aprons 25 and 26, respectively, that are positioned parallel to and closely adjacent the side walls 16 and 17. Although the sides 25-25 of the flap 22 can be offset or formed to meet the sides of the housing

14 where they clear the edges of the sides 26-26 of the flap 23, the sides 25-25 of flap 22 are here shown as having pads 25a-25a attached to the sides to fill the gaps as best illustrated in Figs. 3, 4, and 7. Each of the flaps 22 and 23 are also provided with skirts or arcuate bottoms 27 and 28 which are concentrically formed with respect to the axial center of the supporting pin 24. The upper ends of the flaps 22 and 23 terminate in concentrically shaped overlapping ends 29 and 30 as best illustrated in Figs. 2 and 4.

Thus the flaps 22 and 23 provide elongated cup or trough members cooperating with the housing 14 and forming, together with the box base 15 of the housing, a bellows structure wherein the flaps 22 and 23 may be moved from their full line positions in Fig. 2 into the dotted line positions indicated without providing any definite water bypass from within the tub into the bellows structure or from within the bellows structure into the water column within the tub.

There is communication between the inside of the bellows structure and the water column within the tub 5, however, which is brought about by providing suitable holes in the surface portion of the flaps. These holes may be arranged in predetermined patterns and may be of such selected diameters as to best suit conditions of operation, the holes in flap 22 being indicated at 31 and the holes in flap 23 being indicated at 32. In this connection it may be stated that it is also contemplated to use holes located in the side aprons 25 and 26 of the flaps several of which are indicated at 33 and 34 in Fig. 2. Obviously, suction of water into the holes in the flaps 25 and 26 upon expansion of the bellows will draw water into the bellows structure only when the openings in the side aprons are uncovered when moved beyond the outline of the sides 16 and 17 of the housing 14. Likewise, expulsion of water through such openings in the side aprons will be stopped when the bellows are collapsing by movement of the flaps as such openings again pass within the restrictive confines of the sides of the housing 14.

The operating mechanism for simultaneously moving the flaps 22 and 23 apart and to draw the same together again to operate between the two positions indicated in Fig. 2, is also best illustrated in Fig. 2. This mechanism includes a drive shaft 35 passing through a bored opening 36 axially located within the bearing 18. This drive shaft 35 also passes through a water seal or a stuffing box 37 positioned at the upper end of the bearing 18 for the purpose of preventing water leakage 55 through the shaft bearing and along the main drive shaft.

The upper end of the drive shaft 35 terminates in a pair of cranks 38 and 39 and the stub end 40 of the shaft is journalled in a bearing 41 secured to a cross member 42 extending between the sides 16 and 17 of the housing 14. Connecting links 43 and 44 have ends pivoted at 45 and 46 to the flaps 22 and 23 respectively, while the connecting link 43 is pivotally joined with the crank 39 and the connecting link 44 is pivotally joined with the crank 38 of the main drive shaft 35.

It is seen from the description above that rotation of shaft 35 imparts simultaneous opening and closing respectively of the flaps 22 and 23 with respect to the housing structure 14 producing the expanding and contracting action of the entire agitator bellows head thereby increasing or decreasing the internal capacity of the agitator. Upon the expansion stroke of the bellows, more 75 water will be drawn from the tub water column

into the bellows structure acting to draw the clothes toward the flaps while the flaps are moving outwardly to engage and contact the clothes and adjacent water in the tub. Conversely, contracting of the bellows will cause the water that is trapped within the bellows to eject in streams or jets through the openings 31 and 32 of the flaps 22 and 23 respectively, forcing the clothes away from the receding flaps during this portion of the cycle of operation of the bellows structure.

The ejection of water can also be carried to the box base structure 15 of the housing 14 by providing suitable openings or holes 46a therein as indicated in Fig. 2 which may extend about the periphery of the box base 15. Any water which is expelled out of these openings will diverge along the bottom of the tub 5 and function to turn over clothes and prevent any stagnant situation to develop wherein the clothes may become dormant in this part of the tub.

In addition to the foregoing operation the entire bellows structure is pivotally supported upon the axial bearing 18 as previously described therefore providing a free moving head capable of rotation upon the axial center line portion of the tub and the machine. This motion of the head may or may not be controlled depending upon conditions of operation. In the present construction of agitator unit, it is contemplated to use a pair of flaps or fins 47 and 48 as shown in Figs. 3 and 4 which are pivotally supported at oppositely related corners 49 and 50 of the bellows flaps 22 and 23. The fins 47 and 48 are provided with lugs 51 and 52 respectively, which limit the motion of such fins in counterclockwise rotation when viewed in Fig. 3 but which are arranged to permit counterclockwise rotation of the fins into the dotted line positions 47a and 48a as indicated in this figure. The flat faces of the fins engage the faces of the flaps to limit the maximum water engaging position of the fins indicated in the full line positions in Fig. 3.

From the description immediately above, it is seen that in Figs. 3 and 4 the fins 47 and 48 provide a paddle structure wherein the alternate opening and closing of the two bellows flaps 22 and 23 will also cause the fins to move repeatedly back and forth from the full line positions to their dotted line positions while the flaps 22 and 23 are actuated. When the flaps 22 and 23 open or expand with respect to the remainder of the bellows structure the fins 47 and 48 will be as shown in the full line positions in Fig. 3 bucking the water producing a torque force which will tend to rotate the entire bellows head in the direction of the arrow 55, the water force being diagrammatically illustrated by the arrows 56 and 57. When the flaps 22 and 23 return toward their full line positions as shown in Fig. 2, the fins 47 and 48 will backwater and rotate into their dotted line positions leaving the head in its new angular location with respect to the one immediately prior to the opening and closing of the flaps as described.

Referring back now to Figs. 1 and 2, the shaft 35 for operating the expanding and contracting bellows mechanism extends downwardly through the drive sleeve 20 of the spinning tub 5 through a hub bearing 60 and is driven by means of a motor 3 through the motor pulley 61, belt 62, and the drive pulley 63 secured to the shaft 35. Any suitable drive ratio may be obtained through this drive which is a direct drive from the motor to a single operating shaft located vertically in the axial center line of the washing machine.

A clutch which may be of any desirable construction is indicated at 64 and comprises a plurality of annular driving rings 65 carried for vertical movement upon the driving pins 66 supported from the housing 67 which is secured to the driving sleeve 20 of the spinner tub 5. A plurality of driving discs 68 are secured to the drive shaft 35 and occupy positions between the annular rings 65 in the manner best illustrated in Fig. 2.

10 Pins 66 terminate in suitable heads 69 and 69a and expansion springs 70 normally tend to urge all of the annular rings 65 into tight engagement with respect to the discs 68. An annular operating face plate 71 is slidably carried upon the outer diameter of the driving sleeve 20 and abuts the heads 69a of the pins 66 to provide a means for holding the clutch in inoperative position to permit the shaft 35 to drive the bellows structure directly from the motor 3 through the pulley 61, belt 62 and pulley 63.

When the time comes that the spinner tub is to be operated, the same may be rotated at relatively high speed to sling all of the water and suds from the clothes that have just been washed within said tub. This is accomplished by moving a clutch operating handle 72 that is mounted upon the base 1 and thus rotate a rod 73 carrying a cam 74. The cam 74 engages the end 75 of a rocker arm 76, the latter carrying rolls 77 which normally ride upon the upper surface of the face plate 71. When the handle 72 is moved into "Off" position, the cam 74 is upended to hold the rocker arm 76 in a position with the roller 77 forcing the face plate 71 downwardly to free all of the annular rings 65 from any driving contact with the discs 68. By rotating the handle 72 into its "On" position, all of the springs 70 actuate the rods 66 to clamp the annular rings 65 against the driving disc 68 to complete the drive from the main drive shaft 35 through the clutch to the driving sleeve 20 of the tub 5.

It is natural that the tub 5 and its load of clothes will require a certain interval of time to cause such tub 5 and its driving sleeve 20 to come up to the driving speed of the shaft 35. This difference of rotational speed will be accommodated by the clutch 64 which will eventually automatically reduce the slip between the driving discs 68 and annular rings 65 to solid uniform rotation within a short space of time whereupon the entire tub, clothes, and agitator head are all rotated in synchronism.

During the operation of the washing machine the valve 11 is opened by the user through the 55 operation of the handle 12 immediately after the washing operation interval has been completed permitting a quick drain of the water and suds within the tub 5. Thereafter the spinning operation follows and it is to be noted that during 60 the spinning of the tub 5 the user is entirely protected from contact with the same by reason of the nested and protected relation of the tub 5 within the drain tub 4 and the location of this spinner tub 5 under the lid 6 completely enclosing this fast moving structure. In this connection it may be stated that it is also contemplated using a plug or drain unit 80 to drain the tub 5 before the spinning operation should that be desirable.

70 Other modifications and changes are contemplated in the exact construction shown and described thus far. Figs. 6 and 7 show a modified construction wherein the flaps 22 and 23 are provided with angular faces 81 and 82, respectively, which produce the torque reaction indi-

cated by the arrows 81a and 82a when such flaps expand whereby the entire agitator head is rotated in the direction of the arrow 83. With the latter construction, it is possible to omit the fins 47 and 48 previously described in connection with Figs. 3 and 4 and still obtain the slow angular displacement of the bellows operating unit to obtain a full 360° of agitated action within the water column of the tub. Obviously, the degree of angularity of the faces 81 and 82 with respect to a radial plane intersecting the operating center of the agitator head will determine the speed at which such head is rotated upon its pivotal axis. Also, the holes as previously described and indicated at 31 and 32 may be drilled to direct the water jets coming out of the flaps 22 and 23 in any desirable direction. In other words, the openings may be drilled at right angles to the faces of the surfaces 81 and 82 or at any desirable angle with respect thereto, or radially to the pivotal axis.

Another construction that may be utilized in obtaining the angular displacement of the agitator head is illustrated in Fig. 8. In this case, the box base 15 of the housing 14 has oppositely related groups of openings to produce repulsion jets of water directed in a counterclockwise direction with respect to the axial center of the supported agitator head. Fig. 8 illustrates the box structure 15 as being provided with openings 84 to one side of the transverse vertical median plane 85 of the agitator head, and also with openings 86 in the wall 17 all located to the opposite side of the transverse vertical median plane 85. The operation of this form of agitator head is obvious. Every time the flaps 22 and 23 come together to compress the water within the bellows agitator, the water is forced out of the oppositely related openings 84 and 86 producing repulsion jets which tend to rotate the entire head bodily in the clockwise direction of the arrow 87. Expansion of the flaps 22 and 23 merely draws water into these openings having very little, if any, effect upon the rotational position of the agitator head.

Other modifications and changes in the exact form, combination of parts, and in the exact arrangement of the described washing machine are contemplated. All such changes and modifications or substitution of equivalent mechanisms to perform the functions explained shall be governed by the breadth and scope of the appended claims submitted herewith.

What I claim is:

1. In a washing machine, an agitator for use in the fluid tub thereof comprising a housing with lateral openings including flaps supported for movement into and out of said lateral openings of said housing, operative means to expand and contract the fluid capacity of said housing, said housing and said flaps each having prelocated apertures therein to alternately direct fluid jets into the tub fluid and to draw tub fluid toward and into said housing upon operation of said operative means.

2. An agitator for a washing machine comprising a pivotally supported housing member submerged in the wash water and having an opening therein, a closure member movably connected with said housing member and adapted to substantially close off said opening therein, operative mechanism connected to one of said members to actuate it relatively to the other of said members to alternately produce suction and pressure areas in the water surrounding said members,

and reaction means carried by said housing member to bodily move the housing member and the closure member about the pivotal axis of said housing member.

3. An agitator for a washing machine comprising a pivotally supported housing member submerged in the wash water and having an opening therein, a closure member movably connected with said housing member and adapted to substantially close off said opening therein, operative mechanism connected to actuate one of said members relatively to the other of said members to alternately produce suction and pressure areas in the water surrounding said members, and water reaction means connected with one of said members to provide rotary motion to said housing about its pivotal support while said members are relatively actuated by said operative mechanism.

4. An agitator for a washing machine tub comprising a housing pivotally supported within said tub, said housing having an opening therein, closure members connected with said housing and movably relatively thereto, said closure members being positioned at said housing opening, and operative mechanism for moving said closure members simultaneously away from or toward each other to alternately increase or decrease the water capacity of said housing and to agitate the wash water surrounding said housing, and reaction means responsive to the relative motion of the closure members with respect to the housing to impart rotational motion of said housing about its pivotal support within said tub.

5. An agitator for a washing machine tub comprising a housing submerged in the wash water, bearing means pivotally supporting said housing for free rotation relative to said tub, operative water agitating means movably connected with said housing, and drive mechanism confined within said housing and connected to said agitating means to actuate the same, said mechanism including a drive member passing through said bearing means outwardly of said tub for connection with an external power source.

6. An agitator for a washing machine tub comprising a housing submerged in the wash water, bearing means pivotally supporting said housing for free rotation relative to said tub, operative water agitating means movably connected with said housing, drive mechanism confined within said housing and connected to actuate said agitating means including a drive member passing through said bearing means outwardly of said tub for connection with an external power source, and water reaction means connected with said agitating means to angularly displace said housing relatively to said tub while said agitating means is operated by said drive mechanism.

7. An agitator for a washing machine tub comprising a housing submerged in the water, bearing means pivotally supporting said housing for free rotation relative to said tub, operative water agitating means movably connected with said housing, comprising flaps supported from said housing to move relatively inwardly and outwardly with respect to the pivotal axis of said housing, drive mechanism connected to so operate said flaps, and reaction means to angularly displace said housing relatively to said tub while said flaps are being operated, said reaction means comprising outer surfaces on said flaps angularly disposed with respect to radial planes bisecting the pivotal axis of said housing.

8. An agitator for a washing machine tub comprising a housing submerged in the wash water, bearing means pivotally supporting said housing for free rotation relative to said tub, operative water agitating means movably connected with said housing comprising flaps supported from said housing to move relatively inwardly and outwardly with respect to the pivotal axis of said housing, drive mechanism connected to so operate said flaps, and reaction means to angularly displace said housing relatively to said tub while said flaps are being operated, said reaction means comprising fins pivotally connected with said flaps and arranged to buck the wash water when said flaps are actuated in one direction and to pivotally recede into inactive positions with respect to the wash water when the flaps are actuated in the other direction.

9. An agitator for a washing machine tub comprising a housing submerged in the wash water, bearing means pivotally supporting said housing for free rotation relative to said tub, operative water agitating means movably connected with said housing comprising flaps supported from said housing to move relatively inwardly and outwardly with respect to the pivotal axis of said housing, drive mechanism connected to so operate said flaps, and reaction means to angularly displace said housing relatively to said tub while said flaps are being operated, said reaction means comprising a plurality of apertures in said housing adapted to eject wash water from said housing under the composite action of said flaps when same are actuated in one direction, said apertures being formed in opposite side walls of said housing, the apertures in one wall all being disposed to one side of a vertical transverse median plane of the housing and the apertures in the other wall all being disposed to the other side of the aforesaid plane.

10. A washing machine agitator comprising a hollow housing having openings therein, flaps connected to said housing to swing about a common axis into and out of said openings, said flaps comprising flat members having aprons thereon coacting with the sides of said housing, the outer ends of said flaps being formed with skirts disposed concentrically with respect to the axis about which the flaps swing, and said flaps having overlapping walls adjacent the supporting axis thereof, said aprons, skirts and overlapping walls all functioning to maintain the hollow inclosure of said housing, and operating mechanism to actuate said flaps between predetermined angular limits.

11. A washing machine agitator comprising a hollow housing having openings therein, flaps connected to said housing to swing about a common axis into and out of said openings, said flaps comprising flat members having aprons thereon coacting with the sides of said housing, the outer ends of said flaps being formed with skirts disposed concentrically with respect to the axis about which the flaps swing, said flaps having overlapping walls adjacent the supporting axis 65

thereof, said aprons, skirts and overlapping walls all functioning to maintain the hollow inclosure of said housing, and operating mechanism to actuate said flaps between predetermined angular limits, and apertures in said flaps and housing to expel jets of water therefrom and to draw wash water toward and into said housing.

12. In a washing machine, a stationary casing, a rotatable tub in said casing, an agitator in said tub, said agitator comprising a housing having opposed perforated walls hinged to swing toward or from each other, means extending into said housing for actuating said perforated walls and means for rotating said tub.

13. In a washing machine, a stationary casing, a rotatable tub in said casing, an agitator in said tub comprising a walled housing, means to mount opposed walls of said housing to swing toward and from each other to produce a bellows action and means for simultaneously rotating said tub and actuating said swingable wall parts.

14. In a washing machine, a casing, a rotatable tub in said casing, an agitator in said tub comprising a housing having rigid side walls and movable end walls having flanges in telescopic relation with said side walls, said end walls being adapted for movement toward and from each other to produce a bellows effect, said housing having perforations in said movable end walls and means for rotating said tub and simultaneously actuating said movable end walls.

15. In a washing machine, a casing, a tub rotatable in said casing, an agitator in said tub comprising a housing having opposed swingable wall parts adapted to be swung toward and from each other to produce a bellows effect, movable flaps without said housing connected to said movable wall parts and means for rotating said tub and simultaneously actuating said wall parts for the purpose set forth.

16. In a washing machine, a stationary casing, a rotatable tub in said casing, an agitator in said tub, said agitator comprising a housing having rigid side walls and movable end walls, said end walls having bottom and side flanges in telescopic relation with said side walls, said end walls and flanges having perforations for entrance and exit of washing fluid, and means for rotating said tub and simultaneously actuating said movable end walls for the purpose set forth.
